UNITED STATES PATENT OFFICE.

FREDERICK W. WILD, JR., OF GOVANS, MARYLAND, ASSIGNOR TO BURT MACHINE COMPANY, A CORPORATION OF DELAWARE.

CAN-LACQUERING MACHINE.

942,951.

Specification of Letters Patent. Patented Dec. 14, 1909.

Application filed December 5, 1908. Serial No. 466,036.

To all whom it may concern:

Be it known that I, FREDERICK W. WILD, Jr., citizen of the United States of America, residing at Govans, county of Baltimore, State of Maryland, have invented certain new and useful Improvements in Can-Lacquering Machines, of which the following is a specification.

This invention relates to painting or lacquering machines for treating cans or cylindrical packages. A machine of this type is described in U. S. Letters Patent to Burt, No. 610,165, "Can lacquering machine".

The object of the invention is to provide various parts and combinations of parts by which the machine is rendered more efficient, its output increased and the quality of its work improved.

Though the mechanisms which are the subject matter of my invention are described in connection with a machine which may be correctly termed an improvement upon that of the patent cited, these mechanisms may be otherwise associated within the scope of my invention.

The machine of the patent, briefly described, consists of ways for the cans, an endless traveling belt parallel to the ways and engaging the cans to rotate them, whereby they are advanced along the ways, one or more rotating cylindrical brushes, the axes of which are parallel to the ways, and means for feeding liquid lacquer, paint, etc., to the brushes. The brushes rotate in contact with the heads of the moving cans, coating them with the liquid. Pads or mats of absorbent material to which the coating liquid is fed are placed in the path of the cans. These serve to apply the coating to the can bodies.

My invention provides an automatic spacing device at the feed end of the machine. By means of the spacer, admission of the cans to the machine is timed and they are properly spaced in their passage along the ways. In this way, many defects in the operation of previous machines, as injury to the cans due to contact between them and irregular distribution of the paint or lacquer which occurs if the cans are irregularly or too frequently presented, are overcome.

To maintain continuous contact and uniform pressure of the conveyer belt upon the cans on the ways without injuring the cans or unduly checking their advance, yielding

resilient belt guides are provided. These engage the belts directly over the cans which are being treated and depress the belts into operative engagement with the cans.

At the feed end of the machine, the ways are downwardly inclined so that the cans are propelled into the machine by the force of gravity. As they enter, the cans are conducted to a point below the level at which they are presented to the brushes. A spring placed at the lowest point of the ways is compressed by each descending can and as the downward tendency of each can is checked, the spring expands or reacts and throws the can upward against the conveyer belt and on to the absorbent pad which is between the ways and extends above them when not compressed by the can. If the first contact between the cans and the belt were uncertain or pressure of the belt on the can gradually applied, a considerable amount of slip would occur and the cans would not mount to the pad. By the device of my improvement, firm contact is made immediately when a can is brought into engagement with the belt and the can driven in rotation, by virtue of which rotation it advances over the pad and ways.

In order that cans of various sizes may be treated, the conveyer-belt, pulley and guides are made adjustable vertically relatively to the ways. Each of the cylindrical brushes which act upon the heads of the cans is, with its apron, pulley, etc., adjustable similarly to the conveyer, and also laterally. The ways are also adjustable to cans of different lengths. In this way, it is made possible to adjust the conveyer to admit cans of any size to the ways and to place the brushes with their axes in the plane of the centers of the cans being treated, of whatever size they may be.

Each brush is actuated from the conveyer belt drive by a transmission belt which engages a pulley journaled on the conveyer frame and a second pulley on the brush shaft. As the distance between the brush frame and conveyer frame, and, therefore, between the two pulleys, varies when the machine is adjusted to cans of different sizes, some means must be provided to keep the transmission belt tight. This is accomplished by means of an idler engaging the belt and carried by a spring pressed arm

pivottally mounted on the shaft of one of the transmission pulleys. However, the idler may be otherwise supported.

At the delivery end of the machine, beyond the conveyer belt, the ways are downwardly and rearwardly inclined so that the cans in leaving the machine are propelled by gravity. An absorbent pad or mat is placed along the ways between suitable side guides, and mounted to rotate over the ways, with its axis in a plane substantially parallel to the inclined plane of the ways, is a cylindrical brush. This brush is diagonally placed in regard to the ways and suitable means for rotating it are provided. The brush is spaced above the pad by a distance such that the extremities of the bristles engage the bodies of the passing cans. As the cans advance, the zone of contact moves from one end of each can to the other and the entire surface of the body of the can is acted upon by the brush. Sufficient of the paint or other liquid coating material is conveyed by the cans from the forward brushes to the rear brush and pad, and the rear brush distributes the liquid thus supplied in an even layer upon the can body.

Other features of my invention will be hereinafter described and claimed.

The accompanying drawings illustrate a machine for applying liquid coating to cans. This machine embodies the subject matter of my invention.

Figure 1 is a side elevation of the machine. Fig. 2 is a central transverse cross-section of the machine looking toward the rear. Fig. 2^A is an enlarged view in the plane of Fig. 2, showing the ways with a can thereon in operative position. Fig. 3 is a sectional elevation of the machine taken on a longitudinal plane which is substantially central. The rear brush is so adjusted in this view as not to be cut by the plane of section. The forward portions and the pedestal of the machine are broken away. Fig. 4 is a perspective of the delivery end of the machine. Fig. 5 is a vertical section through the belt tension. Fig. 6 is a perspective of the brushes with their journals, supporting frames and aprons. Fig. 7 is a sectional plan of the ways at the feed end. Fig. 8 is a perspective view of the feed or forward end of the machine. Figs. 9 and 10 are detailed views of the spacing mechanism at successive stages of its operation. Fig. 11 is a plan of the feed end of the machine showing the spacing device.

The can lacquering machine illustrated in the drawings consists of a pedestal 1 on which are mounted horizontal bed-rails 2 parallel to each other and extending in the direction in which the cans are to be fed. The various brackets supporting the different moving parts of the machine are secured to the bed-rails. The ways to be described

are supported by means of the brackets 3 (Fig. 2^A) secured to each bed-rail near each end and near the center. The brackets on the two rails are in pairs, the members of each pair being one on each rail and opposite. Each bracket 3 is provided with an upright arm 4 apertured to receive a transverse rod 5, one mounted on each pair of brackets. The rails or ways 10 are of L-shaped cross-section, the upright arm of the L 25 being outward. They are provided with depending brackets 6 carrying at their lower extremities hubs 7 which receive the rods 5, and are secured thereto by set screws 9. The rods are grooved at 8 to seat the set screws in a plurality of positions of the hubs.

Each bracket 6 is provided with a lug 11 which is apertured to receive an upright post 12, to the upper extremities of which posts the guide rails 13 are secured. It is apparent that the rails and side guides can be adjusted laterally to receive cans of various sizes. This is accomplished by moving the hubs 7 of the arms 6 along the rod 5 and tightening the set screw in their proper grooves 8.

Between the rails and resting on the horizontal arm of the L are pads 14 of absorbent material. These pads are resilient and normally their upper surface is above the upright portion of the L-shaped rail 10. By reference to Fig. 2^A, it will be seen that these pads are compressed by the passing cans so that the edges of the cans rest on the top surfaces of the rails. At the forward end of the machine, a bracket 15 is secured to each bed rail 2, and pivoted to the upright arms 16 of the brackets 15, to swing about a horizontal axis, is a trough 17 for the cans. This trough is supported during the operation of the machine by the removable rod 18 which engages the trough near its outer extremity and extends downward to the forward end of the base of the machine. The trough 17 is considerably wider than the length of the cans to be treated. Secured to the upright sides 18 of the trough near its forward end (Fig. 7) are leaf springs 19, which extend backward and are bent inward toward the center of the trough. The tension and position of these springs is adjustable by means of screws 20 mounted in threaded blocks 21 on the trough. In its normal position, during the operation of the machine, the main body of the trough is inclined downward at a slight angle to the horizontal. At a point slightly beyond the rearward extremities 22 of the springs 19, this angle is increased and the incline of the trough toward the machine is made steeper.

Forward of the brushes, the upright portion 25 of the L-shaped ways 10 is removed, (see Fig. 3) and these ways are inclined, first, downward and forward toward the

feed end of the machine, forming the depression 27, and then upward to meet the rear extremity 26 of the trough 17, forming the incline 28. A leaf spring 29 is secured 5 to each rail 10 at its forward extremity and extends downward to the rear over the depression 27. These springs are deflected upward at a slight angle from the ways for a purpose to be hereinafter described.

10 The pads 14, to which reference has been made, extend backward through the machine from the depression 27, and are supported laterally by the upright portion of the L-shaped ways. The pads are stiffened by a 15 sheet of metal 23 which rests on the horizontal portion of the ways. From a point just beyond the depression 27, the ways 10 are substantially horizontal for a distance equal to about a third of the length of the 20 machine, to a point marked 24 beneath the rear pulley 47 in Fig. 3. From this point to the rear extremity of the machine, they are inclined downward at an angle of about 15°. At the rear end of the machine, (see 25 Fig. 1) is a trough 30 pivoted at its forward extremity to the bed rails 2 and supported at the rear by means of a rod 31 which is secured at its lower extremity to the base plate of the machine. Secured to the forward and central portions of each bed rail 2, (see Figs. 3 and 4) is a bracket 32 in which a vertical rod 33 is mounted. These rods are four in number. Each rod is adjustable vertically and is secured in adjusted 30 position by means of a pin 34 which passes through a hole in the bracket 32 and a suitable hole of a series 35 in the rod. The rod 33 is marked with a series of numbers 36 to correspond to the holes and indicate its adjusted position. Secured to the upper extremity of each rod 33 is a bracket 37 carrying a bearing 38.

Two shafts 39 extending transversely of the machine are journaled at each end in the 45 bearings 38. The rear shaft 39 is driven by a suitable means not shown. Secured to this shaft near its central portion are two pulleys 40 of equal diameter. Two similar pulleys 41 are mounted on the forward shaft 39 and conveyer belts 42 run over the pulleys 40 and 41. The forward and rear brackets 37 at each side of the machine are connected by a horizontal bar 43 (see Fig. 3). Each end of the bar 43 is provided with a depending arm 44 rigidly secured to the rod. Shafts 46 are mounted in the extremities of the horizontal arms 45 of the brackets 37. The lower extremities of the depending arms 44 at each end of the machine are apertured 50 to receive the shafts and mounted on these shafts are guide pulleys 47 which depress the belts 42 to the plane of the upper surfaces of the can bodies on the horizontal portions of the ways. Between the extremities 55 of the bars 43 at the desired intervals, de-

pending arms 48 are rigidly secured. These arms are apertured at 49 (see Figs. 2 and 3). The apertures 49 form ways in which blocks 50 are mounted to slide. In these blocks are journaled shafts 51 upon which 70 are mounted guide pulleys 52. These engage the conveyer belt 42 from above. A spiral spring 53 is placed in each aperture 49, pressing against the upper wall of the aperture and the top of the block 50 to 75 maintain the latter at the lower extremity of the slot. Thus, the pulleys 52 are held against the top of the operative portion of the belt in its normal position. The belt yields upward when sufficient force is applied to the lower surface of the belt to overcome the tension of any pair of springs and move the corresponding guide pulleys 52.

It is apparent that the rods 33 and their brackets 37, the bars 43 and the shafts 39, 80 form a continuous structure which will be known as the conveyer frame. This is adjustable vertically by moving the rods 33 up and down in their supports and securing them in the desired position by means of the pins 34 in the corresponding holes of the series 35. This provides for the treatment of cans of different diameter.

Each forward bracket 37 (see Fig. 8) is provided with a horizontal forwardly extending arm 55 having at its extremity a bearing. A transverse shaft 56 is mounted in the bearings of the two brackets. An arm 57 rigidly secured to this shaft is provided with a follower 58 which engages a cam 59 on the forward shaft 39. A torsion spring 60 encircles the shaft 56 and is secured thereon at one extremity by means of a collar 61. The other extremity of the spring is secured to the bracket 55. The shaft 56 is above the trough 17 and extends across it near the forward extremity thereof and spaced sufficiently from the trough to be out of the path of the largest can to be treated.

Two fingers or stops 62 and 63 (see Figs. 9 and 10) are secured to the shaft 56 at a point over the path of the cans. These fingers are mounted in blocks 162 and 163 apertured to receive the shaft and held by means of set screws 64 and may be adjusted to suit the operator. The fingers are L-shaped, in elevation the end of one arm of the L being secured to the shaft in a radial position and the other arm depending. The lower extremity of the depending arm of each finger is bent inward toward the other so that it extends in a horizontal direction transversely of the machine. The fingers are so placed in regard to their shaft 56 that they are separated by an angle of 120° below. The depending arm of one L-shaped finger is on each side of the shaft 56 and the two depending arms are spaced a distance about one and one third times the diameter of a can. 130

When the cam follower 58 is on the low part of the cam 59, the front finger 62 extends into the path of the cans. When the cam follower is on the high point of the cam (see Fig. 9) this finger is raised and the rear finger 63 extends into the path of the cans. If the finger 63 engaging the forward can of a line be raised by the action of the cam, the front finger 62 descends into the path of the cans, engaging the next one of the line so as to arrest its advance. In this way, at each complete rotation of the forward shaft 39, one can is released. Therefore, the feed of the cans to the conveyer is timed so it is proportionate to the speed of the conveyer belt and the brushes.

Two cylindrical brushes 65 (see Figs. 2 and 6) are mounted on the frame of the machine with their axes parallel to the ways and on a level with the axes of the cans thereon. These brushes are supplied with coating material and rotated to coat the end of the cans. Each brush 65 (see Fig. 6) is secured to a shaft 66 journaled in a bearing member 67 mounted on a horizontal rod 68 which passes through a suitable aperture in a block 168 and is adjustably secured therein by means of a set screw 169. This block is apertured to receive a vertical rod 170 and may be adjusted vertically relatively thereto. The block 168 is apertured to receive a pin 69 which engages any one of a series of holes 70 in the rod 170. A line of numerals 71 is placed on each rod to indicate the position of the brush. Aprons 72 inclosing the brushes from the outside and extending downwardly therefrom to catch the coating material which drips from the brushes are secured to the bearing members 67. These aprons terminate at their upper extremity in a straight edge which is over the brushes and a trough 73 for each apron is secured thereto, extending beyond the edge and depending therefrom. These troughs are perforated at the bottom 74 to allow liquid which is placed therein to drip on the brush below. Each brush shaft is provided at its rear extremity with a pulley 75 secured thereon, (see Figs. 3 and 4). A bevel gear 76 is mounted on the conveyer belt shaft 39 on each side of the machine and each bevel gear 76 engages a companion bevel gear 77 on a stud 78 secured to the bracket 37 at right angles to the shaft 39. A pulley 79 mounted on the stud 78 and secured to the bevel 77 drives a belt 80 which runs over the pulley 75 on the brush shaft and imparts rotation to the brush.

When the conveyer is adjusted to provide for the variation in diameter of the different size cans to be treated, it is apparent that, it must be moved substantially twice as far as the brush is moved to meet the same variation in size of the cans. This is for the reason that the variation of the diameters is

twice that of the radii. In making this adjustment, the distance between the pulleys 79 carried by the conveyer frame and the pulleys 75 carried by the brush frames is varied. To provide for this variation conveniently, an automatic belt tightener is used. This is shown in detail in Fig. 5 which is a vertical section taken along the axis of the stud 78. The belt tightener consists of a radial arm 81 having an elongated hub 82 journaled on the stud 78. At the extremity of the arm remote from the stud is an idler 83 journaled on the arm to bear against the belt 80. A collar 84 mounted on the outer extremity of the stud 78 and held in position by a pin 85 prevents displacement of the hub 82 longitudinally of the stud. A spiral torsion spring 86 encircles the hub and is secured at one extremity to the collar and at the other extremity to the arm 81. The tendency of the spring is to press the idler 83 against the belt and the desired pressure may be secured by withdrawing the pin 85 from the stud and winding or unwinding the spring by rotating the collar. At the desired tension, the pin is replaced in its hole.

At the rear of the conveyer belt, with its axis in a plane above and parallel to the plane of inclination of the rear ways, is a brush 86 (see Fig. 4), the function of which is to distribute the liquid coating over cylindrical can bodies. This brush which will hereinafter be known as the body brush is placed diagonally across the ways; i. e., it extends from a point over one side of the ways just in the rear of the conveyer pulleys to a point over the other side of the ways a considerable distance farther back in the machine and shown as adjacent the rear end of the ways. The body brush is secured to a suitable shaft 87 which is mounted at its forward end to rotate in a bearing member 88. Above and at one side of the ways, this bearing member is secured to the lower end of a depending rod 89 which has a sliding bearing in a block 90 and is secured therein by means of a set screw 91. This block is supported on the shaft 89 between a bevel gear 76 and one of the conveyer belt pulleys 40. The rear extremity of the shaft 87 is journaled in a bearing 92 above and at the opposite side of the ways to the bearing 88. This bearing 92 is carried by a depending arm 93 of a bracket 94. This bracket is apertured to receive an upright rod 95 to which the bracket is secured by means of a suitable set screw 96 (see Fig. 3). The rod 95 is secured at its lower end in a bracket 97 which, in turn, is apertured to receive and secured to a horizontal rod 98 mounted in uprights 99 secured to each bed-rail 2. The block 97 is secured to the rod 98 by means of set screws 100 and rotation of the rod in the brackets 99 is prevented by means of screws 130

101. A pulley 102 is secured to the shaft 87 in the rear of the brush. This pulley is engaged by a belt 103, guided by idlers 104 on the block 105 (see Fig. 3). This belt also 5 engages the pulley 106 on the shaft 39, whereby rotation is communicated to the body brush 86. It will be apparent from this description that the forward end of the body brush may be adjusted vertically by 10 moving the rod 89 through the block 90, and that the rear end of the brush may be adjusted laterally by moving the block 97 along the rod 98, and vertically by moving the block 94 along the upright rod 95.

15. In the operation of the machine, cans are placed in the trough 17 (see Fig. 8). The inclination of this trough gives them a tendency to move to the rear into the machine propelled by the force of gravity. The cans 20 are centered in the trough by means of the springs 19 (see Fig. 7). These springs press against the heads of the advancing cans and guide them as they approach the spacing device. At this stage of the operation, the 25 finger 62 is depressed and the finger 63 raised (see Fig. 9); the cam follower 58 being on the low portion of the cam 59. The first can of the line comes in contact with the finger 62 and its advance is arrested. As the rotation 30 of the cam continues in the direction of the arrow in Figs. 9 and 10, the follower passes from the low part of the cam to the high part. The lever 57 oscillates downward, moving the shaft 56 through a similar 35 angle; the finger 62 is raised and releases the first can. By this operation, the finger 63 is depressed into the path of the cans and the can released by the finger 62 is engaged thereby. Further revolution of the cam 59 40 brings the follower again on to a high portion of the cam track, whereby the finger 62 is lowered and the finger 63 raised. The can which recently rested against the finger 63 is released and moves forward into the machine and another can moves forward against 45 the depressed finger 62. In this way, at each complete revolution of the forward shaft 39, one can is fed into the machine. As each can is released by the finger 63, it passes down 50 the incline 26 of the trough 17 on to the forward end 28 or incline of the ways 10. As the can moves down the incline of the trough and the ways, it gathers a considerable amount of momentum, and the spring 29 55 which in its normal position is deflected upward into the path of the cans is depressed. As the can reaches the bottom of the depression 27, its downward momentum is checked by the ways and the reaction of the spring 29, the forward portion of which is under the can in this position, throws the latter upward against the conveyer belt 42 which drives it in rotation. The cylindrical surface of the can now engages the pad 14 60 and the can rolls forward on the pad by 65 virtue of the rotation imparted to it by the belt. The pressure of the can on the pad, due to the weight of the can and the action of the belt, compresses the mat or pad 14 and it yields sufficiently to allow the edges 70 of the can to engage the upper surfaces of the rails 10, the upright portions 25 of which have their front ends just back of the depression 27. The belt is maintained in contact with the upper element of the cylindrical surface of the can by its tension and by the pressure due to the yielding guide rollers 53. The cans are thus rotated by the belt substantially without slip. They roll 75 forward along the ways 10, *i. e.*, to the right, 80 as seen in Fig. 3. During the passage of the cans along the horizontal portion of the ways, their ends are brushed continually by the rotating brushes 65 to which the liquid coating is fed from the perforated troughs 85 74, as previously described. Spattering and spraying of the liquid is prevented by the aprons 72 which conduct such portions of the liquid as are thrown upward or outward from the brushes to the trough 172 which is 90 drained into a suitable receptacle 173. The liquid which is thrown downward is retained by the pad and smeared on the cylindrical bodies of the cans.

It is important to note that the conveyer 95 belts, the brushes, the aprons and the ways are adjustable to receive cans of any length or diameter within the desired limits. As has been set forth in connection with Fig. 2^a the side rails 13 and the ways 10 may be 100 adjusted laterally at the will of the operator, providing for cans of any length which may be used. By reference to Fig. 6, it is apparent that the brushes with their covers may likewise be adjusted laterally by 105 sliding the rods 68 horizontally through the blocks 168 and securing them in adjusted position by the set screws 169. To provide for cans of different diameters, the conveyer 110 belts 42 with their driving pulleys 40 and carrier pulleys 41 and the guide pulleys 47 and 53, with the conveyer frame upon which they are mounted, may be adjusted vertically by sliding the rods 33 through the brackets 32 and placing the pins 34 in the 115 appropriate holes of the series 35. These holes are so placed as to accommodate cans of the sizes used in the trade. In order that cans of different diameters may be properly treated by the end brushes 65, these brushes 120 are made adjustable vertically so the axes of the brushes may be kept in the plane of the can centers. This is done by sliding the blocks 168 along the upright rods 170. The blocks are secured in adjusted position by 125 inserting the pins 69 in the appropriate holes of the series 70 in the upright rods. These holes are placed to correspond to the different sizes of cans and are numbered for the convenience of the operator, as previously set 130

forth. By numbering the holes and advising the operator as to the particular adjustment to be had, very little is left to his judgment. The functions and the operation of the belt tightener have been previously described and further description thereof is thought to be unnecessary. As the can leaves the end brushes 65, it passes beneath the rear guide pulleys 47 of the conveyer belt and out of contact with the latter. From the depression 27 to this point 24 beneath the rear guide pulley 47, the ways are horizontal. From this point (see Fig. 2^A) *i. e.*, beneath the rear guide pulleys 47, the ways are given a downward and rearward inclination whereby the cans are propelled in their passage by the force of gravity. As a can gathers speed on the incline, it comes in contact with the cylindrical body brush 86 which serves to distribute over the can body the coating liquid already applied thereto by the pads 14. In this connection it is important to note that the liquid for coating the can bodies is fed to the end brushes 65 only and enough of this liquid to coat the cylindrical bodies of the cans is thrown by the brushes 65 and becomes deposited on the pads during the operation of the machine, and some of this liquid, after continuous operation of the machine, becomes distributed over the brush 86. As the can first comes in contact with the brush 86, a zone on the can body adjacent one end is engaged by the brush. As previously described, the brush extends to the rear and diagonally across the ways, so that as the can advances the zone of contact moves from one end of the can to the other and the whole surface is thoroughly treated. The adjustments of the brush 86 and its drive have been previously described; further notice thereof is unnecessary.

This machine, though described as for applying lacquer, may be used, and is used, for cleaning cans. In this case, stiff wire brushes may be substituted for the bristle brushes shown and no lacquer used. As the cans pass out of contact with the brush 86, they reach the end of the ways and of the pan 14 and are delivered to the troughs 30 (see Fig. 1). This trough is provided with longitudinal rails 150 shown in the form of angle irons. These serve to raise the cans so the coating on their cylindrical surfaces is not rubbed. The contacting edges of the rails are so thin that they remove but very little of the liquid, forming a fine line over which the liquid closes before drying takes place. A stop 131 may be placed at the end of this trough to arrest the advance of the cans so that they may be removed by the operator, or they may be delivered at this point to a suitable receptacle or to another conveyer.

Having thus described my invention, what

I claim and desire to secure by Letters Patent is:

1. In a machine for treating cans, ways, means for spacing the articles on the ways consisting of a plurality of radial fingers 70 the extremities of which are deflected horizontally, a rock shaft to which the fingers are secured, a cam, a follower for the cam connected to the rock shaft, and means for rotating the cam to oscillate the fingers so that they move alternately into and out of the path of the cans. 75

2. In a machine for treating the surfaces of cylindrical packages, ways for the packages, means adjacent the way for applying 80 the coating material, a belt to impart rotary motion to the packages while being coated, a portion of the ways along which the packages move toward the coating means being inclined downward in the direction of travel 85 of the packages, a spring in the path of the packages at the bottom of the incline, which is flexed by the packages as they descend and throws the packages upward against the belt. 90

3. In a machine for coating the surfaces of cans, ways along which the cans roll, having an inclined portion and a horizontal portion, the feed end of the ways inclined in the direction of motion of the cans, a conveyer belt over the horizontal portion of the ways, a spring over the ways at the base of the incline whereby the cans, as they descend, compress the spring, and as their downward momentum is checked, the packages are thrown upward against the belt. 95

4. In a machine for applying liquid coating material to the surfaces of cans, ways, means for spreading the coating material over the surfaces of the cans, a belt over the ways for rotating the articles and moving them past the coating means, a depression near the forward end of the ways, a spring over the depression and in the path of the cans, and means for checking the advance of 100 each can as it rests on the compressed spring. 105

5. In a machine for treating the surfaces of cans with liquid, ways, means adjacent the ways for applying liquid, a belt over the ways for rotating the cans and moving them by the coating means, a depression near the forward end of the ways, a spring in the depression to be compressed by the cans entering the depression, the path of the cans, as they approach the depression, being inclined to give them a downward momentum, whereby the spring is compressed by the cans entering the depression and as they reach the bottom of the depression their momentum is checked and they are thrown upward 110 by the recoil of the spring. 115

6. In a machine for coating the surfaces of cylindrical packages, ways for the packages, means adjacent the package for applying 120 the coating means, a belt over the ways 125

to impart rotary motion to the packages while being coated, a portion of the ways along which the packages move being inclined downward in the direction of the motion of the cans, a spring extending along the ways and deflected into the path of the packages at the bottom of the incline, the packages, as they descend, flex the spring, and when their momentum is checked the reaction of the spring throws the cans upward against the belt.

7. In a machine for coating the surfaces of cans, ways, coating means adjacent the ways, the ways being inclined downward in front of the coating means, an absorbent pad between the ways normally expanded to extend above the ways, springs on the ways near the bottom of the incline extending into the path of the cans, so that the cans flex the spring in their descent, and as their descent is checked are thrown upward on to the pad by the reaction of the spring.

8. In a machine for applying liquid coating to the surfaces of cylindrical packages, ways for the packages, a belt above the ways for rotating the packages to move them along the ways, means adjacent the ways for applying coating material to the packages, the forward end of the ways being inclined downward toward the coating means, a spring on the incline extending into the path of the packages so that it is flexed by the packages as they descend, and as the descent of the packages is checked they are thrown upward by the reaction of the spring against the belt and driven in rotation thereby.

9. In a machine for treating cylindrical packages, ways along which the packages roll on their cylindrical surfaces, a brush above the ways and extending diagonally across the ways, and spaced therefrom, and means for rotating the brush.

10. In a machine for treating cylindrical packages, ways along which the packages roll on their cylindrical surfaces, a brush, the axis of which is in a plane substantially parallel to the ways, the brush extending diagonally across the ways and spaced therefrom a distance slightly less than the diameter of the packages, and means for rotating the brush.

11. In a machine for treating cans, ways inclined downward to the rear along which the cans roll on their cylindrical surfaces, a brush, the axis of which is in a plane substantially parallel to the ways, extending diagonally across the ways and spaced therefrom a distance slightly less than the diameter of the cans, and means for rotating the brush.

12. In a machine for treating cans, ways along which the cans roll on their cylindrical surfaces, a brush above the ways extending diagonally across the ways, spaced

therefrom a distance slightly less than the diameter of the cans, means for rotating the brush, and means for adjusting both ends of the brush vertically and one end horizontally.

13. In a machine for coating cylindrical packages, ways along which the cans roll on their cylindrical surfaces, an absorbent pad in the path of the packages, means for supplying coating material to the pad, a brush extending across the ways and spaced therefrom a distance slightly less than the diameter of the packages, and means for rotating the brush.

14. In a machine for applying liquid coating to cylindrical cans, ways along which the cans are rolled in succession, brushes for applying coating material to the ends of the cans, means for supplying liquid coating to the brushes, a pad adjacent the brushes and in the path of the cans, a body brush over the ways beyond the end brushes, and means for rotating the body brush to distribute the liquid over the cylindrical surfaces.

15. In a machine for applying liquid coating to cylindrical packages, ways along which the cans roll, brushes adjacent the ways for applying liquid coating to the ends of the packages, means for supplying the liquid to the brushes, means for catching part of the liquid from the brushes and bringing it in contact with the cylindrical surfaces of the packages, a body brush over the ways in the rear of the end brush, means for actuating the body brush to distribute the liquid over the cylindrical surfaces of the packages.

16. In a machine for applying liquid coating to cylindrical packages, ways along which the cans roll, end brushes for coating the ends of the packages, means for supplying liquid to the brushes, a pad extending along the ways to catch part of the liquid from the brushes to bring it in contact with the cylindrical surfaces of the packages, a body brush over the ways in the rear of the end brushes, extending diagonally across the ways, and means for rotating the body brush to distribute the coating over the cylindrical surfaces of the packages.

17. In a machine for applying liquid coating to cans, ways for the cans, a brush adjacent the ways for applying coating material to the ends of the cans, a conveyer belt to rotate the cans and roll them along the ways past the brush, means for adjusting the position of the conveyer belt and the brush to accommodate cans of various sizes, a belt operatively connecting the conveyer belt and the brushes, and means for maintaining the tension of the latter belt constant to provide for unequal adjustment of the connected members.

18. In a machine for applying liquid

coating to cans, ways for the cans, a brush adjacent the ways for applying coating material to the ends of the cans, a conveyer belt to rotate the cans and roll them along the ways, means for adjusting the position of the conveyer belt and the brush to accommodate the various sizes of cans, a belt operatively connecting the conveyer and the brushes, means for maintaining the tension of the belt constant, consisting of a pivotally mounted arm, a torsion spring, one end of which is fixedly secured and the other applied to the arm; and an idler mounted on the free end of the arm and pressed against the belt by the spring.

19. In a machine for treating cylindrical cans, ways along which the cans are rolled in succession, brushes to engage the ends of the cans, a body brush over the ways beyond the end brushes, and means for rotating the body brush in contact with the surfaces of the cans.

20. In a machine for treating cans, ways, and a belt for rotating the cans, and means for maintaining the pressure of the belt against the cans constant consisting of yielding guides placed at intervals along the belt.

21. In a machine for treating cans, ways, a belt for rotating the cans, and means for maintaining the pressure of the belt against the cans constant, said means consisting of guide pulleys, sliding blocks in which the pulleys are journaled, and springs bearing on the blocks and pressing the pulleys against the belt.

22. In a machine for treating cylindrical cans, ways along which the cans are rolled, a brush side of the ways to engage the ends of the cans, and a brush above the ways extending along the ways to engage the cylindrical surfaces of the cans.

23. In a machine for treating the surfaces of cans with liquid material, ways, means adjacent the ways for applying the liquid, a conveyer frame, pulleys on the frame, means for driving one pulley, a conveyer belt on the pulley, and means for supporting the frame, consisting of uprights and bearings in which the uprights may be moved in the direction of their length, and means for securing the uprights in adjusted position.

24. In a machine for treating the surfaces of cans with liquid material, ways, means adjacent the ways for applying the liquid, a conveyer frame, pulleys on the frame, means for driving one pulley, a conveyer belt on the pulley, and means for supporting the frame, consisting of uprights and bearings in which the uprights may be moved in the direction of their length, and means for securing the uprights in a series of predetermined positions.

25. In a machine for treating the sur-

faces of cans with liquid material, ways, means adjacent the ways for applying the liquid, a conveyer frame, pulleys on the frame, means for driving one pulley, a conveyer belt on the pulley, and means for supporting the frame, consisting of uprights and bearings in which the uprights may be moved in the direction of their length, and means for securing the uprights in a series of predetermined positions consisting of a series of holes and a coöperating pin for each upright.

26. In a machine for treating the surfaces of cans with liquid material, ways, means adjacent the ways for applying the liquid, a conveyer frame, pulleys on the frame, a belt running over the pulleys, guide pulleys on the conveyer frame to depress the belt into operative relation to the ways, and yielding guides on the conveyer frame to maintain the belt in operative relation to the cans on the ways.

27. In a machine for treating the surfaces of cans, ways, brushes for engaging the ends of the cans on the ways, a conveyer frame, a conveyer belt and pulleys on the conveyer frame, and means for adjusting the frame vertically to provide for the treatment of cans of various sizes.

28. In a machine for treating the surfaces of cylindrical packages, a pair of rails forming ways for the packages, means for supporting the ways, including a plurality of transverse rods upon which the rails are mounted, and means for securing the ways to the rods in a plurality of positions whereby they may be adjusted to receive cans of various sizes.

29. In a machine for treating the surfaces of cylindrical packages, a pair of rails forming ways for the packages, and means for supporting the ways, including a plurality of transverse rods upon which one of the rails is mounted, and means for securing that rail to the rods in a plurality of positions whereby they may be adjusted to receive cans of various sizes.

30. In a machine for treating the surfaces of cans, ways along which the cans roll, means for supporting the ways whereby they may be adjusted laterally, brushes adjacent the ways for applying liquid to the cans, and means for supporting the brushes whereby they may be adjusted laterally.

31. In a machine for treating the surfaces of cans, ways along which the cans roll, means for supporting the ways whereby they may be adjusted laterally, brushes adjacent the ways, means for rotating the brushes, and means for adjusting their position both laterally and vertically, a conveyer belt over the ways to actuate the cans, and means for adjusting the conveyer belt vertically.

32. In a machine for treating the surfaces

of cans, ways along which the cans roll, brushes adjacent the ways, means for rotating the brushes, means for supporting the brushes whereby they may be adjusted vertically, a conveyer belt over the ways, means for supporting the belt whereby it may be adjusted vertically.

33. In a machine for applying liquid coating to the surfaces of cans, means for distributing the coating, means for moving the cans past the coating means, and means for supporting the cans after they pass the coating means, consisting of upright blades extending in the direction of travel.

34. In a machine for applying liquid coating to cans, the combination of a feeding trough, side springs for centering the cans in the feeding trough, means for releasing one can at a time from the centering means and stopping the rest until the released cans have moved a desired distance.

Signed by me at Baltimore, Maryland, this 3rd day of December 1908.

FREDERICK W. WILD, JR.
